United States Patent Office

Des. 193,114
Patented June 26, 1962

193,114

SPECTACLE FRAME

Murray E. Green, New York, N.Y., assignor to Zylite Products Co., Inc., New York, N.Y., a corporation of New York

Filed Mar. 13, 1961, Ser. No. 64,246

Term of patent 7 years

(Cl. D57—1)

FIG. 1.

FIG. 2.

FIG. 1 is a front perspective view of a spectacle frame, showing my new design.

FIG. 2 is a top plan view of FIG. 1.

The dominant features of my design reside in the portions shown in full lines.

I claim:

The ornamental design for a spectacle frame, as shown and described.
